UNITED STATES PATENT OFFICE

2,573,884

REMOVABLE SHOT MAGAZINE FOR
PNEUMATIC GUNS

William S. Wells, Palo Alto, Calif., assignor to
Daisy Manufacturing Company, Plymouth,
Mich., a corporation of Michigan

Application July 21, 1947, Serial No. 762,392

5 Claims. (Cl. 124—45)

1

This invention relates generally to guns and refers more particularly to improvements in pneumatic guns.

One of the objects of this invention is to facilitate loading of single action pneumatic guns by providing means on the gun barrel for removably supporting a shot holding magazine.

Another object of this invention is to provide a magazine in the form of a tube adapted to hold a predetermined number of shot, and capable of being readily attached to the gun in a position enabling the shot to be quickly transferred from the magazine to the breech end of the barrel.

A further feature of this invention is to provide a delivery tube secured to the gun in a position immediately adjacent the shot loading opening in the breech end of the gun barrel and having the entrant end registerable with the delivery end of the magazine to receive shot from the latter.

A still further object of this invention is to provide an arrangement of the above type which does not appreciably add to the weight of the gun and does not interfere with sighting or handling the gun.

The foregoing as well as other objects will be made more apparent as this description proceeds, especially when considered in connection with the accompanying drawing, wherein:

Figure 1 is a fragmentary perspective view of a gun having a magazine assembly embodying the features of this invention;

Figure 2 is a longitudinal sectional view through the magazine assembly;

Figure 3 is a fragmentary plan view partly in section of the breech end of the gun shown in Figure 1;

Figure 4 is a cross sectional view taken on the plane indicated by the line 4—4 of Figure 2;

Figure 5 is a cross sectional view taken on the plane indicated by the line 5—5 of Figure 2; and

Figure 6 is a fragmentary longitudinal sectional view of a part of the magazine assembly.

It will be understood as this description proceeds that the magazine assembly forming the subject matter of this invention may be advantageously used in connection with various different types of single action guns designed to fire shot of either the ball or pellet types. For the purpose of illustrating this invention, however, the magazine assembly is shown in connection with a single action pneumatic gun of the general type shown and described in detail in my copending application Serial No. 762,391, filed July 21, 1947, and now abandoned.

2

It is not essential for a complete understanding of this invention to define the action of the gun, and therefore, this specification will not be complicated by a detailed description of the particular gun illustrated. It will suffice to point out that the gun comprises a stock 10 and a frame 11. The frame 11 in turn comprises a barrel 12, a storage chamber 13 for air under pressure and a supplementary storage chamber 14. The storage chamber 13 is in the form of a tube, and is located directly beneath the barrel 12 in the manner clearly shown in Figures 4 and 5 of the drawings. The supplementary storage chamber 14 is also in the form of a tube, and is supported directly beneath the storage chamber 13. As indicated in Figure 1 of the drawings, the storage chamber 14 is somewhat shorter than the chamber 13, and communicates with the latter in a manner not shown herein.

20 The breech end of the barrel 12 is shown in Figure 3 of the drawing as having an opening 15 through the top wall into which shot either of the ball or pellet type may be inserted. The opening 15 is normally concealed by a sleeve or cap 16 suitably supported on the frame 11 at the breech end of the barrel 12 for sliding movement longitudinally of the gun frame. In the actual construction of the gun the cap 16 is connected to the cocking mechanism (not shown) for cocking the gun, and is also connected to a firing pin, also not shown, for propelling the shot to its firing position in the barrel 12 upon forward movement of the cap 16. The cocking mechanism is released to fire the shot through the barrel 12 by a trigger 17 housed in a trigger guard 18 in accordance with conventional practice.

The present invention concerns itself more particularly with the means for conveniently and quickly reloading the barrel after each shot, and this is accomplished herein by the provision of a magazine assembly indicated generally in the drawing by a reference character 19. The magazine assembly 19 comprises a pair of brackets 20 and 21 mounted on the barrel 12 at points spaced from each other longitudinally of the barrel. A tubular housing 22 is welded or otherwise permanently secured to one side of the bracket 20, and is positioned with its axis extending parallel to the axis of the barrel 12. A plunger 23 is supported in the housing 22 for sliding movement and has a stem 24 which projects rearwardly through an opening in the rear end of the housing. The plunger 23 is normally maintained in a position at the rear end of the housing 22 by a coil spring 25 located in the housing 22 at the

front end of the plunger 23. The rear end of the coil spring 25 abuts the plunger 23, and the front end of the coil spring engages a plug 26 threadedly mounted in the front end of the housing 22.

A bushing 27 is welded or otherwise permanently secured to the rear bracket 21 in axial alignment with the housing 22 and a tube 28 is sleeved in the rear end of the bushing 27. The tube 28 is welded to the bushing 27, and the rear end of the tube projects beyond the corresponding end of the bushing in the manner clearly shown in Figures 1 to 3 inclusive of the drawing.

The internal diameter of the tube 28 is predetermined to freely slidably receive shot, such for example, as pellets P. In Figure 6 of the drawing, a plurality of pellets P are shown in position in the tube 28, although it will be understood that the tube will accommodate other types of shot. It will also be noted from Figure 6 of the drawing that a pair of elongated slots 29 are formed in diametrically opposite sides of the tube 28 at the rear or breech end of the latter. The rear ends of the slots 29 are open and the width of the slots is sufficient to enable the user to grasp the pellets between the thumb and forefinger when it is desired to extract a pellet from the delivery end of the tube. Accidental removal of the pellets P from the rear or delivery end of the tube 28 is prevented by means of a spring clip 30 having the front end fixed to the underside of the tube 28 and having the rear end curved upwardly to assume a position in registration with the rearwardmost pellet P in the tube 28. The strength of the spring 30 is merely sufficient to hold the pellets P against removal from the tube under the action of gravity, and may be readily overcome by the user when it is desired to extract a pellet from the delivery end of the tube. Referring now to Figure 3 of the drawings, it will be noted that the delivery end of the tube 28 is located in relatively close proximity to the opening 15 in the breech end of the barrel 12, so that a pellet or shot may be quickly transferred from the delivery end 28 to the opening 15.

The shot or pellets are supplied to the tube 28 by a tubular magazine or holder 31. The front end of the tubular magazine 31 is formed with a socket 32 adapted to receive the rear end of the stem 24 on the plunger 23, and the breech or rear end of the magazine is adapted to be sleeved into the front end of the bushing 27 in the manner clearly shown in Figure 2 of the drawing. The construction is such that the rear or delivery end of the magazine 31 registers with the entrant end of the tube 28 to enable the transfer of pellets or shot from the magazine 31 to the tube 28. The length of the tubular magazine 31 is somewhat greater than the normal distance between the rear end of the stem 24 and the front end of the tube 28, so that when the magazine is in its assembled position, the spring 25 is under compression. Thus the spring acts through the plunger 23 and cooperates with the bushing 27 to hold the magazine 31 in assembled position.

The magazine 31 has an internal diameter corresponding to the internal diameter of the tube 28 and freely slidably retains a plurality of shot. The arrangement is such that in the assembled position of the magazine 31 on the gun the tube 28 may be replenished with shot by merely tilting the muzzle end of the gun upwardly at an angle sufficient to enable shot to slide downwardly into the tube 28 by the action of gravity. When the magazine is exhausted of shot, the latter may be readily interchanged with another magazine filled with shot by merely sliding the

magazine forwardly sufficiently to disengage the rear end of the magazine from the bushing 27. During this operation the plunger 23 is moved forwardly in the housing 22 to further compress the spring 25. However, as soon as the rear end of the magazine is released from the bushing 27, the spring 25 returns the plunger to its rearwardmost position. The magazine filled with shot is then assembled on the gun by merely engaging the socket 32 on the front end of the magazine with the rear end of the plunger stem 24 and by inserting the rear end of the magazine into the front end of the bushing 27. The spring 25 is, of course, compressed by the plunger 23 to enable assembling the rear end of the magazine with the bushing 27 and remains under compression subsequent to the above assembly in order to yieldably retain the magazine in place.

What I claim as my invention is:

1. A shot retaining magazine assembly for a gun having a barrel, comprising a bushing supported at one side of the barrel with its axis extending substantially parallel to the barrel axis, means for securing the bushing to the barrel including a bracket secured to one side of the bushing and having a laterally extending portion shaped to extend over the barrel, an elongated tube adapted to slidably support a plurality of shot with the shot arranged in a row extending lengthwise of the tube and having the front end portion sleeved within and secured to the bushing, said tube being open at the rear end to enable successive removal of shot from the rear end, and yieldable means positioned in obstructing relation to the rearwardmost shot in the tube for normally retaining said shot within the tube.

2. A shot retaining magazine assembly for a gun having a barrel, comprising a bushing supported at one side of the barrel with the axis extending substantially parallel to the barrel axis, a tube sleeved within the bushing and having the front end portion terminating short of the corresponding end of the bushing, a second tube adapted to slidably support a plurality of shot and having the rear end portion sleeved within the front end of the bushing in abutting engagement with the adjacent end of the first tube, and means supported at one side of the gun barrel and removably engaging the front end portion of the second tube.

3. A shot retaining magazine assembly for a gun having a barrel, comprising a bushing supported at one side of the barrel with its axis extending substantially parallel to the barrel axis, a shot retaining tube sleeved within and secured to the bushing with the front end thereof terminating short of the corresponding end of the bushing, said tube having the rear end projecting beyond the rear end of the bushing and having circumferentially spaced slots through the rear end portion thereof enabling the rearwardmost shot in the tube to be gripped by the user, a second tube positioned with the rear end thereof slidably engaging within the front end of the bushing and adapted to abut the front end of the first tube to form in effect a continuation of the latter, and means supported at one side of the gun barrel and removably engaging the front end of the second tube.

4. A shot retaining magazine assembly for a gun having a barrel, comprising a stationary tubular member supported at one side of the gun barrel with its axis extending substantially parallel to the barrel axis, a plunger slidably supported in the tubular member and having the

rear end projecting beyond the corresponding end of the tubular member, spring means in said tubular member acting on the plunger normally urging the same in a rearward direction, a tube adapted to slidably support a plurality of shot with the shot arranged in a row extending lengthwise of the tube, said tube having its front end closed and having a recess therein for removably receiving the rear end of the plunger, and a stationary member supported at one side 10 of the gun barrel and slidably receiving and supporting the rear end of said tube.

5. A shot retaining magazine assembly for a gun having a barrel, comprising a bushing supported at one side of the barrel with its axis extending substantially parallel to the barrel axis, a tube extending rearwardly from the bushing and having the front end sleeved in the bushing, the front end of said tube being secured in the bushing and terminating short of the front end of said bushing, a tubular member supported at one side of the gun barrel in axial alignment with the bushing, a plunger slidably supported in the tubular member and having the rear end projecting beyond the rear end of said tubular member, spring means supported in said tubular member acting on the plunger normally urging the same in a rearward direction, a tube adapted to slidably support a plurality of shot

with the shot arranged in a row extending lengthwise of the tube and having the rear end slidably supported in the front end of the bushing to form a continuation of the first tube, and 5 means closing the front end of the second tube providing a recess for removably engaging the rear end of the plunger.
